[57] **ABSTRACT**

Three cylindrical battery cells are physically disposed in a plastic housing with two of the cells spaced coaxially adjacent one another and the third cell spaced later-

ally adjacent the coaxial cells spanning the distance between the coaxial cells. An insulating band encircles the end of each cell, between the end cap and a current-collecting sleeve, to prevent shorting between the current collectors. The three cells are connected electrically by conductive elements, such as end caps or straps, that place the third cell in series between the coaxial cells.
